UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed October 3, 1921. Serial No. 505,137.

To all whom it may concern:

Be it known that I, JOHN WALDHEIM, a citizen of the United States, residing in Elizabeth, in the county of Union, and 5 State of New Jersey, have invented certain new and useful Improvements in Typewriting Machines, of which the following is a specification.

This invention relates to sound-deadening casings for typewriting machines.

It is one feature of this invention to provide a casing completely enclosing the noise-producing parts of the machine, but so constructed that it may be readily removed 15 from the machine and collapsed by folding it out to a flat condition to occupy a minimum amount of space for convenience in shipping or storing.

Another feature of this invention is the 20 construction of the casing in such manner that it may be readily set up by any operator.

According to the present embodiment of the invention, the casing comprises a body-part 25 having a removable front plate to permit insertion of the machine into the casing, and a cover-part or cover. The body-part and cover-part are both hollow and are hinged together, and each part comprises 30 hinged walls, so that when said front plate is removed the parts may be substantially flattened out and swung together, to occupy a minimum amount of space. To set up the casing it is only necessary to swing the body-part and cover-part to open position about 35 the hinge which connects them, and then swing the various walls of each part to their effective set-up positions. Suitable devices 40 may be provided to hold the parts in their effective positions.

This invention is in the nature of an improvement on my co-pending applications No. 475,061, filed June 4, 1921, No. 476,765, filed June 11, 1921, the application of B. C. 45 Stickney, No. 473,018, filed May 27, 1921, and application of G. W. Campbell, No. 500,514, filed September 14, 1921. The claims in this case are limited to organizations that are not disclosed in said applications.

Other features and advantages will hereinafter appear.

In the accompanying drawings,

Figure 1 is a perspective view of a sound-deadening casing. 55

Figure 2 is a perspective view of said casing in its collapsed or folded position.

Figure 3 is a vertical section of the sound-deadening casing applied to an Underwood Standard typewriter. 60

Figure 4 is a front elevation, partly sectioned, of the device shown in Figure 3.

Figure 5 is a transverse section of the sound-deadening casing in its collapsed position. 65

Figure 6 is a front elevation, partly sectioned vertically, of the device shown in Figure 5.

The Underwood Standard typewriting machine comprises a main frame 10, supported upon a base by feet 11, said main frame having a forward extension 12 in which are positioned banks of keys 13 for operating type-bars 14 to cause types 15 carried thereby to print against a platen 16, 70 journaled in a platen-frame 17, the types 15 being arranged in an arc at the front of the machine. Said platen-frame forms part of a carriage 20 mounted for letter-feeding movement on a front rail 21 and a rear rail 80 22 on the main frame. The carriage is provided with forwardly-extending operating handles, such as line-space handle 23. 75

For deadening the sounds arising in the typing operation, there is provided a sound-deadening casing comprising a body-part 30 and a cover-part 31, the body-part enclosing the main frame 10, and the cover being hollow to enclose the carriage 20. 85

Said body-part comprises a base 32 for supporting the machine, a pad 33 of sound-deadening material being preferably interposed between the feet 11 of said machine and said base, side walls 35 extending outwardly and upwardly to provide space within which the typewriter carriage may operate to the right and left, a rear wall 36, and a removable front wall or plate 37, said front plate, when removed, providing a large opening at the front through which 90

said machine may be inserted into the casing, the machine being located by holes 38 in the pad 33. The removable plate 37 is provided with a depending portion or tongue 49 for closing the arcuate opening 100 24 in the usual cover-plate 25 attached to 105

the front of the machine in which arcuate openings are positioned the types 15 of the type-bars. To permit access to the type-bars without removing the casing or the 5 front plate 37, as for the purpose of cleaning the types, the depending portion may be provided with an opening 50 which is closed by a removable plate 50 supported in said opening by hook-shaped pins 51 fixed 10 thereto and by a detent-spring 52. The plate is thus readily removed or attached, a knob 53 being preferably provided for facilitating handling.

To permit said body-part to be collapsed, 15 said front plate is first removed and the machine withdrawn from said body-part, and the side walls and rear wall are then disconnected and swung outwardly into the plane of the base. To permit said walls to be 20 swung on said base, the side walls are hingedly connected to said base at 39, and the rear wall 36 is hingedly connected to said base at 40. To hold said walls in their effective set-up positions, the side 25 walls may be provided with lugs 42 which lie adjacent the rear wall, fastening members, herein shown as screws 43, being passed through said rear wall and into said lugs. To enable the front plate to be mounted 30 upon said body-part, the side walls may be provided with lugs 45 adjacent the front of the body-part, fastening members 46 being passed through said front plate and into said lugs 45.

35 The body-part, when set up, thus completely encloses the machine, with the exception of the forward extension 12, at the bottom, sides, front, and rear, and to enclose the machine at the top, there is provided the 40 cover-part 31. Said cover-part comprises a rear wall 55, side walls 58, a top wall or ceiling 56, which extends forwardly and slopes downwardly, and has preferably positioned therein, a window 57 to permit the machine 45 in the interior of the casing to be viewed. The side walls 58 of the cover-part overlap the side edges of the body-part, the downward movement of the cover-part being limited preferably by pins 54 on the side walls 50 58 engaging the side walls 35 of the body-part. Said ceiling 56 terminates in a short front wall 60, positioned some distance above the top of front plate 37 to provide a slot through which extend the forwardly-extending 55 carriage-operating levers, such as the line-space handle 23, to be operable from outside of the casing, said slot being closed by co-operating sound-deadening cushions 61 and 62 mounted upon the front wall 60 and 60 the front plate 37, respectively. To permit the cover-part to be flattened out, the rear wall and side walls thereof are released and then swung about the top wall 56 substantially into the plane of said top wall. For 65 this purpose, the rear wall 55 is hinged to

the rear edge of the top wall 56 at 65 and the side walls 58 are hinged to the side edges of said top wall at 66. To maintain the walls of the cover-part in their set-up positions, the side walls 58 may be provided with lugs 70 adjacent the rear wall 55, screws 71 being passed through said rear wall 55 and into said lugs. The side walls and ceiling 56 of the cover may be fastened at the front by screws 71^a passing through the side walls or end plates 58 and threaded into lugs 70^a on the ceiling.

When said body-part and said cover-part have been flattened out substantially into the plane of the base 32 and the top wall 56, respectively, these parts may be folded one upon the other, the rear wall 55 of the cover-part being hingedly connected to the rear wall 36 of the cover-part at 67.

When the sound-deadening casing is set up and applied to the machine, it is desirable to provide means for assisting in raising the cover-part when access to the machine is desired. For this purpose, a spring 75 may be provided, said spring being connected to a lug 76 fixed to the body-part and to a hook 77 fixed to said cover-part, said spring thus tending normally to swing the cover-part to open position. For limiting the upward movement of the cover-part, a stop 78 fixed to the body-part may be interposed in the path of hook 77. When the casing is to be collapsed and the walls swung outwardly, it is necessary to detach said spring. This may be readily accomplished by merely lifting one end of the spring off hook 77.

The casing may, if desired, be supported upon feet 80 similar to feet 11, said feet being preferably attached to the base 32.

It will be understood that the casing may be lined in any suitable manner with sound-deadening material.

It should be understood that to enable the casing to be flattened out as much as possible the hinge 65 connecting the rear wall 55 and the ceiling 56 of the cover as seen in Figures 3 and 5 is located about midway of the curved part of the cover. It should also be understood that the distance from the hinge 67 to the hinge 65 is shorter than the distance from the hinge 67 to the hinge 40. This condition avoids interference between the hinge 65 and the hinge 67 when the casing is collapsed and aids in compacting the casing, the hinge 65 falling to one side of the hinge 40, as indicated in Figure 5.

Variations may be resorted to within the scope of the invention, and portions of the improvements may be used without others.

Having thus described my invention, I claim:

1. The combination of a typewriting machine including a main frame and a carriage, a sound-deadening cabinet includ-

ing two main parts, namely, a body-part and a cover-part to enclose the machine while the latter is in use, the body-part being hollow to fit around the main frame, the cover-
5 part being hinged on the body-part and being hollow to confine the carriage and swingable at will to open the casing from front to back to give access to the machine, each main part being composed of sections,
10 so that it may be folded out to flat condition to be packed for shipment and erectable for use with the machine.

2. The combination of a typewriting machine including a carriage, a sound-deadening cabinet including two main parts, namely, a body-part and a cover-part to enclose the machine while the latter is in use, the cover-part being hinged on the body-part and extending over the carriage, each main
15 part being composed of sections, so that it may be folded out to flat condition to occupy a minimum of space for convenience in storing or shipping, and so that it may be erected for use with the machine, means
20 to secure the cover-sections to each other, and means to secure the body-sections to each other, so that when erected the cover may be swung at will as an integral part on the erected body-part to open the casing to give access to the carriage.

3. A foldable sound-deadening casing for a typewriting machine composed of two main parts, namely, a machine-receiving body-part and a hollow cover-part, the body-
25 part having a base to support the machine, a rear wall hinged to the base and side walls hinged to the base and flared outwardly at the top to accommodate the travel of the typewriter carriage, the cover-part having a back wall hinged at its lower edge to the rear wall of the body-part and curved forwardly at its upper edge, a downwardly and forwardly inclined ceiling or forward section curved to merge with the curved
40 portion of the upper edge of the back wall when in normal relation therewith, said ceiling being hinged at its upper rear edge to the rear wall, the hinge being disposed about midway of the curve of the cover-part formed by the rear wall and the forward section, so as to decrease the space occupied thereby to a minimum when folded out, and side walls shaped to fit the edges of the back wall and said forward section or ceiling hinged to the forward section at its edges.

4. A foldable sound-deadening casing for a typewriting machine including a carriage, comprising a machine-receiving body-part
60 with lateral overhangs formed by end walls to accommodate the travel of the typewriter carriage, and a cover having a rear wall hinged at its lower edge to the body-part at a position below the carriage and curved forwardly at its upper edge, side walls and

a forwardly and downwardly inclined ceiling hinged at its rear edge to the upper edge of the rear wall and curved adjacent its rear edge to merge with a curved portion of the rear wall, the adjacent curved portions of the ceiling and rear wall being of substantially the same area to enable the ceiling and rear wall to be flattened as much as possible when the casing is folded, the rear wall and the ceiling of the cover extending over a rear wall and base, respectively, of the body-part, and the side walls of the cover extending over the end walls of the body-part when the casing is folded out to flat condition.

5. A sound-deadening casing for a typewriting machine having a frame, types arranged in an arc at the front of the machine, a keyboard extension and a front plate having an arcuate opening to give access to the types for cleaning, said casing comprising a cover and a body-part having a front wall to fit around said keyboard extension and co-operate with the frame and the front plate of the machine to partially close the front of the casing without closing the arcuate opening, and a plate to close the arcuate opening in said front plate, said plate being also provided to open the arcuate opening to permit access to the types for cleaning without otherwise disturbing the casing.

6. A sound-deadening casing for a typewriting machine having a frame, a keyboard extension, types arranged in an arc at the front of the machine above the keyboard extension and a front plate on said frame having an arcuate opening to give access to the types for cleaning, said casing comprising a body-part having a rear wall and overhanging side walls to accommodate the travel of the typewriter carriage, a cover, and a front closure for the casing having an opening through which the keyboard extension projects and having a tongue projecting downwardly into the upper part of said keyboard opening in said front closure to close the opening in the front plate of the machine, said tongue comprising a removable portion opposite the opening in said front plate to permit access to the types without removal of the front closure as a whole.

7. A sound-deadening casing for a typewriting machine having a main frame and a carriage, said casing comprising two main parts, namely, a body-part and a cover-part, each of said parts comprising sections hinged to each other to permit said parts to be flattened out, lugs on certain sections of each part, and fastening means passing through the ends of said sections adjacent said lugs and through said lugs to fasten the adjacent sections of each part together in the set-up position of the casing to form

the body-part to fit around the main frame and the cover to fit around the carriage, the cover being hinged on the body-part and swingable thereon freely as an integral part 5 to open and close the casing.

8. A sound-deadening casing for a typewriting machine, said casing comprising a body-part and a cover-part, said body-part comprising a base, side walls, a rear wall, and a removable front plate, said walls being hinged on said base to permit said body-part to be flattened out when said front plate is removed, said side walls having lugs adjacent the side edges of the rear wall, fastening means passing through said side edges of the rear wall and said lugs to hold said walls together in the set-up position of the casing, said side walls having front lugs, fastening means passing through 20 the side edges of said front plate and said front lugs for mounting said front plate upon said side walls, said cover-part comprising a ceiling, a rear wall, and side walls, the walls of the cover-part being hinged on 25 said ceiling to permit said cover-part to be flattened out, said side walls of the cover-part having lugs adjacent the free side edges of said rear wall of the cover-part, and fastening means passing through said rear wall 30 of the cover-part and through said last-named lugs to hold said cover-part walls together in the set-up position of the casing.

9. A foldable sound-deadening casing for a typewriting machine having a carriage 35 with a forwardly-projecting handle, comprising a body-part having a base, side walls, a rear wall and connecting hinge therefor, the hinges connecting the base and rear wall projecting inwardly, a cover comprising 40 a rear wall of different height from the rear wall of the body-part, a ceiling, side walls and connecting hinge therefor, the hinges connecting the ceiling and rear wall of the cover projecting inwardly, an inwardly-projecting hinge connecting the rear wall 45 of the body-part and the rear wall of the cover, the arrangement of parts being such that, when the rear wall of the body-part is swung downwardly to the rear and the 50 rear wall of the cover is folded thereon, the hinge connecting the rear wall and ceiling of the cover will fall to one side of the hinge connecting the rear wall and base of the body-part, a closure plate for the front of 55 the casing and forming with the forward edge of said ceiling a slot through which said handle projects, and cushions on the adjacent edges of said ceiling and closure plate, the cushion on the forward edge of the ceiling resting on said base when the casing is 60 folded.

10. A foldable sound-deadening casing for a typewriting machine, comprising a machine-receiving body-part having a base to 65 support the machine, a rear wall hinged to

the base and side walls hinged to the base and flared outwardly at the top to accommodate the travel of the typewriter carriage, a cover having a back wall hinged at its lower edge to the rear wall of the body-part 70 and curved forwardly at its upper edge, a downwardly and forwardly inclined ceiling hinged at its rear edge to the rear wall and curved to merge with the curved portion of the upper edge of the back wall when in 75 normal relation therewith, and side walls shaped to fit the edges of the back wall and ceiling and hinged to the ceiling at its edges, an arm extending downwardly from one of the side walls of the cover near the rear, a 80 lug on the corresponding side of the body-part at the front, and a cover-assisting spring to connect said arm and lug to urge the cover upwardly, the spring being readily detachable to avoid interference when it 85 is desired to fold the casing.

11. A sound-deadening casing for a typewriting machine, comprising a body and a cover part forming together a box-like casing for enclosing the machine, the parts, 90 and the elements thereof, connected to fold flat, one part upon the other; the body having an opening in the front wall thereof through which the keyboard of the machine may extend, and means within the casing to 95 position the machine with respect to the casing.

12. A sound-deadening casing for a typewriting machine, comprising a body and a cover part forming together a box-like casing for enclosing the machine, the parts, and the elements thereof, connected to fold flat, one part upon the other; the body having an opening in the front wall thereof through which the keyboard of the machine 100 may extend, and means within the casing to position the machine with respect to the casing, said means including a lining of sound-deadening material on the base of the body 105 and provided with openings for the feet of the machine. 110

13. The combination with a typewriting machine having a main frame and carriage, of a sound-deadening cabinet including two main parts, namely, a body-part and a 115 cover-part to enclose the machine while the latter is in use, the cover-part having a window through which the typing being done may be observed, said cover-part being hinged to the body-part and being hollow to 120 confine the carriage and swingable upwardly and rearwardly at will to open the cabinet at the top from front to back to give access to the machine, the cover-part being composed of sections including two end walls, the body-part being hollow to fit around the main frame and being composed of sections including two end walls, the end walls of the body-part being inclined 125 upwardly and outwardly towards the end 130

walls of the cover-part, the body-part being foldable out to a flat condition, and the cover-part being foldable out to flat condition to spread over the flattened-out body-
5 part.

14. The combination of a typewriting machine including a carriage, a sound-deadening cabinet including two main parts, namely, a body-part and a cover-part to close the machine, the cover-part being hinged on the body-part and extending over the carriage, the body-part being composed of sections including a base, a rear wall hinged on said base, side walls hinged on

said base so that the body-part may be folded out to flat condition, and a front wall, said front wall having an opening therein through which the keyboard section of the machine may extend, said front wall being detachable from the body-part to enable the 15 machine to be placed within the body-part after the body-part has been set up, the front wall being passed over the keyboard extension to be attached to the front of the body-part, and devices to secure said walls 20 25 together.

JOHN WALDHEIM.
